(57) **CLAIM**

The ornamental design for a strap assembly for a sock as shown and described.

DESCRIPTION

FIG. 1 is a front perspective view of a strap assembly for a sock.

FIG. 2 is a rear perspective view thereof.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof; and,

FIG. 9 is a front perspective view of a strap assembly for a sock shown in an alternative environment.

The long dash broken lines depict the sock environment and form no part of the claimed design. The short dash broken lines within the strap assembly portions with surface shading depict stitching and form no part of the claimed design.

1 Claim, 9 Drawing Sheets
